3 Claims. (Cl. 254—24)

This invention relates to gripping and pulling devices and more particularly to a device adapted to pull anchor plates off from the floors of railway cars.

In order to secure heavy articles to the floors of railway cars in which they are being shipped anchor plates are frequently nailed or spiked to such floors, and when the shipper is through with using such plates it is desirable that they be removed. Owing to the secure manner in which the plates are nailed or spiked to the car floors this is a difficult operation to perform. Hence it is an important object of the present invention to provide a tool for quickly and efficiently doing what has hitherto been a difficult, tedious operation.

Although, as aforesaid, the invention is particularly intended to be used as an anchor plate puller, it is by no means limited to such use, but can be used in a variety of situations where powerful gripping and pulling operations are required.

An object of the invention is to provide a more sturdily built gripping and pulling device wherein great leverage may be safely applied to a pair of powerful gripping jaws without danger of breaking the tool.

A more specific object is to provide an improved combination of gripping jaws, mounting means for said jaws, and means for forcibly causing rollers to act upon cam surfaces on said jaws to force them to gripping position.

Additional objects, advantages and features of invention will hereinafter appear.

Referring to the accompanying drawings, illustrative of a preferred, reduced to practice embodiment of the invention,

FIG. 1 is an elevation of the complete device positioned with the operating lever directed toward the observer.

FIG. 2 is a side elevation looking at the device, as shown in FIG. 1, from right to left.

FIG. 3 is a cross-section on line 3—3 of FIG. 1, on a somewhat larger scale.

FIG. 4 is a partly sectional and partly elevational, larger scale view of the applicator end portion of the tool, the line 4—4 on FIG. 2 indicating the plane of the sectioned portion of the view.

FIG. 5 is a transverse section on a still larger scale, the plane of the sectioned portion of the view being indicated by the line 5—5 on FIG. 1.

In FIG. 6 the lower end portion of FIG. 1 is reproduced on an enlarged scale, parts of the device nearest to the observer being removed to disclose underlying structure. In this view the gripping portions of the jaws are shown nearer to each other with a plate gripped between them.

FIG. 7 is a large scale, elevational view illustrating the lever operated means for retracting the carriage upon which are mounted the rollers which actuate the gripping jaws. The two pawls shown in this view are in engagement with the ratchet upon which they act.

FIG. 8 is, for the most part, a reproduction of the showing of FIG. 7, but the pawls are disengaged from the rack.

FIG. 9 is a sectional detail on line 9—9 of FIG. 7.

FIG. 10 is a cross-section on line 10—10 of FIG. 7, parts below the plane of section being omitted.

FIG. 11 is a perspective illustrating the means whereby

2

articles are secured to the floors of railway cars to hold them in place during transit.

FIG. 12 is an elevation illustrating how the device is used to withdraw an anchor plate from a car floor.

Referring in detail to the drawings, and mentioning first the main features of the structure shown, the device comprises a hollow bar 15, which forms a part of a member which may be described as of an inverted T-shape, owing to the fact that it has bolted to its jaw carrying end portion a pair of transversely extending plates 16; a pair of gripping jaws 17 having arms 18 provided internally with cam faces; a pair of rollers 19 which act upon said cam faces; a carriage 20 upon which said rollers are mounted, said carriage being slidable along the bar 15; and lever operable means for retracting said carriage illustrated in FIGS. 7, 8 and 9, retracting said carriage causing said rollers to act upon the aforesaid cam faces and thus swing the jaws toward gripping position.

The invention resides principally in the structure illustrated in FIGS. 3, 4, 5 and 6, but also in part in the lever operable carriage retracting means.

By preference and as shown, the bar 15 is made of a very thick sheet metal and is rectangular in cross-section. The cross plates 16 abut flatwise against the opposite narrower sides of said bar and are secured thereto by bolts 21 and 22, the latter bolt extending through ears 23 projecting from the mid-length portions of the plates. Said plates are thus firmly secured to the bar, and form a good means for mounting the jaws 17, which are positioned between the plates and are swingably fastened to them by means of bolts 24.

A tension spring 25 on each side of the device tends to swing the jaws to open position. Clips 25a fasten the end portions of these springs to the end portions of bolts 26 which pass through the jaws.

Each of the aforesaid jaw arms is tapered, but is of a sturdy character to bear severe strain. Each jaw arm is provided internally with an arcuate cam surface 31 upon which one or the other of the rollers acts when the carriage 20 is retracted to swing the jaws toward the gripping position.

The already mentioned slidably mounted carriage 20 comprises a pair of parallel, spaced apart, flat plates 32, said plates being secured to each other by bolts 33 and pins 33a, said bolts also serving to pivotally mount the rollers 19. Said plates are shown recessed at 34 so as, at times, to accommodate the ears 23 of plate 16.

The means for retracting the carriage 30 comprises four metal straps 36 which, as is to be seen in FIGS. 1 and 2, have their lower end portions attached to the end portions of the aforesaid bolts 33, the upper end portion of each of said straps being twisted through a right angle to adapt it for being bolted to one of the four flange portions 37 of a rectangular in cross-section sleeve 38 which is movable along the bar 15. In FIG. 10 the bolts 38a which pass through the upper end portions of the straps are shown carrying anti-friction rollers 38b and 38c which facilitate the movement of the sleeve 38 along the bar 15.

Said sleeve 38 carries, preferably integral therewith, a pair of spaced apart flanges 39 between which, upon a pivot bolt 39a, is swingably mounted an operating lever 40 which, in turn, is connected by a pair of links 41, to a driving lever 42 which operates pawls, next to be described, which act upon ratchet teeth 15a to retract the sleeve 38 along the rod 15. Said lever 42 swings upon a bolt 42a.

Said lever 42 has swingably secured to it, and acted powerfully upon by it, a downwardly directed main pawl 45. With this pawl co-operates a holding pawl 46 which also co-operates with the rack 15a, to prevent retraction of the bar 15, after it has been acted upon by the main pawl 45. A tension spring 47, one portion of which is coiled around the bolt 43, and another portion of which is coiled around the aforesaid bolt 42a, is so mounted that one of its end portions normally tends to swing the main pawl 45 into engagement with the rack while its opposite end portion tends to swing the holding pawl against the rack.

The linkage 41, which connects the operating lever 40 with the driving lever 42, is connected with the operating lever nearer to its fulcrum than it is to the fulcrum of the driving lever, so as to exert a powerful leverage upon the latter lever.

The pawl adjusting means comprises a cam carrying lever 50 (see FIGS. 7 and 8) swingably mounted on a pin 51 between the lower portions of flanges 39. This lever co-operates with a pawl control plate 52, swingable upon a pin 53. A tension spring 54 causes said pawl control plate to oppose movement of said lever from the position of FIG. 8 to the position of FIG. 7. One end of this spring is secured to the pin 51 and its opposite end is secured to an ear 52e on the plate 52. At its upper end said plate 52 carries a finger 56 which acts upon a pin 57 carried by the holding pawl 46, and has a cam surface which engages a pin 59 carried by the driving pawl 45, to release the latter pawl.

When the cam carrying lever 50 is swung from the position of FIG. 8 to the position of FIG. 7 it will allow both the spring loaded pawls 45 and 46 to come into engagement with the rack 15a, so that repeatedly down-swinging the levers 40 and 42 will move the sleeve 38 upwardly, and by means of the metal straps 36 will draw the rollers 33 upwardly causing them to act upon the cam surfaces of the jaw arms 18 in such a manner as forcibly to move the jaws toward gripping position. The teeth 15a upon which the pawls act are formed in an inexpensive manner by providing one wall of the sheet metal tube with a series of indentations.

In FIGS. 6 and 12 an anchor plate 60 is shown, the latter view illustrating how said plate is withdrawn from the car floor 61 even though secured thereto by spikes 62.

In FIG. 11 a box 64 is shown secured by straps 65 to the anchor plates 60. After the box has been removed the device will be used as illustrated in FIG. 12 to remove the anchor plates.

The plate gripping part of each jaw is shown provided with an acutely angular recess 67 positioned to engage the anchor plates as illustrated in FIG. 12. These recesses co-operate with the arcuate exterior jaw surfaces to pull off anchor plates when the applied tool is swung as illustrated in FIG. 12. The plate being pulled off abuts the inner wall of each of said angular recesses and is thus positively held against sliding in relation to the jaws.

When the cam lever 50 is in the down position of FIG. 8 the pawls are disengaged from the rack, and consequently the rods 36 together with their mounting means and the jaw carrying carriage 20 are rendered freely movable downwardly along the tubular bar 15 to a position for gripping an anchor plate 60 as illustrated in FIGS. 6 and 12. Then, after swinging the cam lever up to the position shown in FIG. 7, the workman will operate the lever 40 to cause the jaws forcibly to grip the anchor plate to be pulled off, preparatory to operating the tool as illustrated in FIG. 12.

It will be observed that the angular recesses 67 in the gripping jaws co-operate with the outer surfaces of the jaws to form acutely angular jaw corners adapted to be wedge under opposite edge portions of the plates to be pulled off.

Although we have illustrated and described what is

deemed to be a preferred embodiment of the invention, yet it is to be understood that various changes, within the scope of the appended claims, may be made without departing from the spirit of the invention.

We claim:

1. A tool of the kind described comprising an elongated member of an inverted T-shape, a jaw swingably carried by each arm of the T and swingable in the same plane as the stem of the T, said jaws having gripping end portions positioned to engage in axial alignment with said stem and slightly spaced away from the jaw carrying end thereof, a carriage slidably mounted on said member between portions of said jaws, two rollers carried by said carriage, each of said jaws having a cam surface engaged by one or the other of said rollers to swing the gripping end portions of said jaws toward each other, and lever operated means carried by the bar and operatively related to said carriage to retract it and thereby cause said rollers to force said jaws toward gripping position, said rollers at all times occupying a protected position between said jaws.

2. A tool of the kind described comprising an elongated member of an inverted T-shape, a jaw swingably carried by each arm of the T and swingable in the same plane as is occupied by the stem of the T, said jaws having gripping end portions positioned to engage objects in axial alignment with said stem and slightly spaced away from the jaw-carrying end thereof, a carriage slidably mounted on said member, said carriage comprising a pair of parallel, spaced apart plates each slidably overlying in a flatwise manner one side of said member, bolts bridging the space between said plates and having end portions projecting outwardly from them, rollers turnably mounted on said bolts between said plates, said jaws having cam portions spaced from said gripping end portions upon which said rollers act to move said gripping end portions toward the gripping position, a sleeve slidably mounted on said elongated member in a spaced relation to said carriage, traction connections linking said sleeve with the aforesaid projecting end portions of said bolts, and means carried by said sleeve and acting on said elongated member to retract said sleeve together with said traction connections, thus to also retract said carriage and cause said rollers to swing the jaws toward gripping position.

3. A tool of the kind described comprising a bar having side portions along one of which is a rack, a sleeve slidably mounted on said bar, a driving pawl and a holding pawl carried by said sleeve in an operative relation to said rack, a driving lever connected with said sleeve and operatively connected with both of said pawls, an operating lever connected with said sleeve and linked to said driving lever by linkage connected nearer to the fulcrum of the operating lever than to the fulcrum of the driving lever so as to impart additional leverage to the latter lever and more forcibly cause said driving pawl to act upon the rack, a pair of gripping jaws carried by an end portion of said bar and considerably spaced away from said sleeve, a carriage mounted slidably on said bar adjacent to said jaws, rollers mounted on said carriage, said jaws having cam faces engageable with said rollers so that the latter may be utilized to move the jaws toward gripping position when said carriage is moved farther away from that end portion of the bar upon which the jaws are mounted, traction connections linking said sleeve to said carriage so that retraction of said sleeve will also retract said carriage and cause said rollers to move the jaws toward gripping position, and a pawl release means carried by said sleeve and manually adjustable to disengage said pawls from the rack so that, after the tool has been operated, the sleeve and carriage can be manually slid along the bar to the limit of their movement toward the jaw carrying end thereof.
